UNITED STATES PATENT OFFICE.

JAMES E. MAYHEW, OF BROOKLYN, NEW YORK.

ALARM-CLOCK JACKET.

Application filed July 6, 1925. Serial No. 41,607.

This invention relates to paper containers and the main object is to provide a container which is adapted to house a small ornamental clock or the like. The clock for which the container is designed to serve a purpose, is mounted or set upon a buffet or mantelpiece and in time becomes quickly coated with dust or any other dirt particles suspended in the air. The container serves to completely enclose the front of the clock and cover the same so that the dirt or dust settles upon the container which may be readily discarded when desired.

The above and other objects will become apparent in the description below, in which characters of reference refer to like-named parts in the drawing.

Referring briefly to the drawing, Figure 1 is a perspective view of the container blank before the process of folding.

Figure 2 is a sectional elevational view thru the container.

Figure 3 is a perspective view of the container in folded position, a part thereof being broken away to illustrate the formation of the platform upon which the clock stands within the container.

Referring in detail to the drawing, Figure 1 illustrates the blank from which the container is formed. This blank is of an integral piece of rigid and bendable material such as paper or the like. The blank consists of a rectangular central piece of material 10 which has its upper corners cut away to provide a semi-circular upper edge 11. At the top of this semi-circular upper edge, an additional connecting flap 12 is integrally joined with the central portion 10. This connecting flap has a width of material 14 integral therewith which serves as the closure flap and bends on the dotted line 15. The sides of the central portion 10 are integral with side walls 13 and 16 which are bent at right angles to the plane of the central portion 10 on the dotted lines 17. From the lower edge or bottom of the central portion, a plurality of flaps, at least four in number, and indicated by the numerals 18, 19, 20, and 21, successively join each other and are integral with the bottom edge of the central portion 10. These flaps are positioned side by side, one successively following the other and are bent on the lines 22 to form a hollow support after being

folded into a square, the flap 20 serving as a platform while the flaps 19 and 21 serve as legs upon which the platform 20 is supported. The leg flap 19 has ears 23 extending from its ends which are adapted to be folded on the dotted lines 24 to close the ends of the hollow structure formed by bending the flaps 18, 19, 20, and 21. Their relation to the container is illustrated in Figure 3. The central portion 10 of the blank has a relatively large opening 25 thru which the dial or face of the clock, which is supported upon the platform flap 20, is visible.

This container, as illustrated, is adapted to be used with clocks which have a semi-circular top, but it is to be understood that such clocks as have different shapes at their upper ends, such as octagonal or many sided flats thereon, only necessitate the changing of the outline or semi-circular edge 11 of the central portion of the blank. The side walls 13 and 16 and the connecting flap 12 are of approximately the same width and are folded at right angles to the central portion 10 to provide a container having a bottom and side walls. To construct the container from the blank, as illustrated in Figure 1, the side walls which are of slightly greater length than the length of the central portion 10, are folded upon the line 17 to an upright position, the upper or free ends of these sides 13 and 16 being curved around the semi-circular edge 11 of the central portion 10. The ends 26 of the sides 13 and 16 are mutually spaced-apart and have a space between them which is covered by the connecting flap 12 as it folds on the line 27 externally over the ends 26 of these sides. When this connecting flap has been folded in this manner, the closure flap is folded downwardly and inwardly on the dotted line 15 so that said closure flap attains a position parallel to the connecting flap and beneath the ends 26 of the sides 13 and 16. The four flaps 18, 19, 20, and 21, which extend from the opposite end of the central portion 10, are folded on the line 22 and are of the same general width. These flaps are all folded in the same direction and when so folded, provide a rectangular hollow box-like structure of which the flap 20 serves as a platform, resting upon legs 21 and 19, which serve as legs upon which the platform stands. The ears 23 are then folded toward each other to close the ends of the rectan-

5 gular structure formed by the folding of the four-named flaps and also aids in giving rigidity to the platform. The container is now completely folded and its lower end 10 must be secured in position so that the same will not unfold. The container is secured against unfolding by a pair of ears 28 and 29 which may have one of their faces treated with glue. These ears extend from the 15 lower ends of the sides 13 and 16 and fold on the lines 30. These ears, when the container is fully folded, seat upon the external surface of the flap 18 and may be glued thereto, as desired. A small clock may then 20 be inserted into the chamber of the container to rest upon the platform flap 20 and its face or dial may be visible thru the opening 25 from which the time of the day may be indicated.

20 I claim:—

1. A sanitary container for a clock comprising a sheet of material formed of one piece, a central portion forming part of the material adapted to cover the front of a 25 clock, sides integral with the central portion and adapted to be folded at right angles thereto, said central portion having a semi-circular upper edge to conform to a clock of similar outline, a platform integral with the 30 central portion, the latter having an opening for the dial or face of the clock, a connecting flap joining the semi-circular edge of the central portion and adapted to cover the 35 ends of the sides which are integral with the central portion, a closure flap extending from the connecting flap and adapted to fold

parallel to the connecting flap, thereby securing the ends of the side pieces or walls between the connecting flap and closure flap.

2. A sanitary container for clocks comprising a sheet of material formed of one piece, a central portion forming part of the material adapted to cover the front of a clock, sides integral with the central portion and adapted to be folded at right angles thereto, said central portion having a semi-circular upper edge to conform to a clock of similar outline, a platform integral with the central portion, the latter having an opening for the dial or face of the clock, a connecting flap joining the semi-circular edge of the central portion and adapted to cover the ends of the sides which are integral with the central portion, a closure flap extending from the connecting flap and adapted to fold 55 parallel to the connecting flap, thereby securing the ends of the side pieces or walls between the connecting flap and closure flap, said platform comprising a plurality of flaps joined integrally side by side and 60 adapted to be folded at its joined positions, said flaps being four in number to provide a rectangular hollow housing in which one of said flaps serve as a platform in the container, and ears at the lower ends of the side pieces covered with glue for securing the lower ends of the side walls around the central portion of the blank to form a container.

In testimony whereof I affix my signature.

JAMES E. MAYHEW.
